UNITED STATES PATENT OFFICE.

VICTOR ANGERER AND WILLIAM SELFRIDGE, OF PHILADELPHIA, PENNSYLVANIA; SAID WILLIAM SELFRIDGE EXECUTOR OF EDWARD SAMUEL, DECEASED.

RAILROAD-TRACK STRUCTURE.

SPECIFICATION forming part of Letters Patent No. 693,210, dated February 11, 1902.

Application filed November 21, 1896. Serial No. 613,025. (No model.)

To all whom it may concern:

Be it known that VICTOR ANGERER, a citizen of the United States, residing at Philadelphia, Pennsylvania, and EDWARD SAMUEL, formerly a citizen of the United States, residing at Philadelphia, Pennsylvania, but now deceased, did during the lifetime of said EDWARD SAMUEL invent certain Improvements in Railroad-Track Structures, of which the following is a specification.

The object of the invention is to provide a rail structure, such as a crossing or frog, with a hard-metal plate set in the center, this hard-metal plate being confined to those portions of the structure which have to sustain more wear than the adjoining rails; and a further object is to provide a gradual change of bearing of the wheel from the hard metal to the softer metal, or vice versa. Heretofore it has been the practice to make the hard-metal centers of considerable length, so that portions of these hard-metal centers receive no more wear than the adjoining rails, thereby causing uneven wear within the center itself, and it further has been the practice to make the joint between the hard-metal center and the adjoining rails square or nearly square, thereby making an abrupt change from the hard metal to the softer metal of the rail, making in time an uneven track.

In the accompanying drawings, Figure 1 is a perspective view of a crossing structure illustrating the invention. Fig. 2 is a plan view. Fig. 3 is a longitudinal sectional view of Fig. 1. Fig. 4 is a perspective view of the center plate.

Referring to Fig. 1, which illustrates a crossing structure in which the rail A crosses the rail B, it will readily be seen that the diamond-shaped portion in the center is subjected to the travel on both rails A and B on one part, while the other parts have to sustain the traffic on a reduced width of bearing-surface of the wheel. It is necessary, therefore, to leave out or cut out the rails within this diamond-shaped space and insert a plate D, through which plate are cut grooves d to continue the flangeways in the crossing-rails.

The practice heretofore in use was to insert hard plates in the structure. These plates, however, would extend beyond the diamond-

shaped space, and the parts within this space would wear faster than the portions outside of it, and ridges would therefore form where they cross the tread of the rail.

Referring again to Fig. 2, it will be seen that a wheel traveling on rail A in the direction of arrow 1 will at point m on the tread part of the structure commence to leave the bearing on the head of the rail and gradually take a partial bearing on the hard center plate, until at a point opposite n it will bear only on the center plate. At point s it will commence to leave the center plate and gradually take a bearing on the rail, until at a point opposite t it again has a full bearing on the rail. This will insure smooth running of the wheels and will tend to equalize the wear, while in the old methods the abrupt change from a hard metal to a softer metal would quickly work a depression into the softer metal just beyond the joint.

It will be understood that when the wear of the wheels is spoken of it not only refers to the vertical wear by the tread, but also to the side wear by the flanges, both of which, as will be seen, are provided for in the hard center plate.

What is claimed is—

1. The combination in a crossing structure, of the rails forming said structure, a diamond-shaped plate mounted in that portion of the structure where the rails would cross each other, said diamond-shaped plate having flangeways cut therein forming four diamond-shaped projections, substantially as described.

2. The combination in a crossing structure, of the rails forming said structure, a cast-metal joint-block by which the rails are secured together, a cavity in the said joint-block, a hard-metal center plate mounted within said cavity and having flangeways forming four diamond-shaped projections, substantially as described.

3. The combination in a crossing structure, of the rails forming said structure, the ends of the rails being cut at an angle, a cast block by which the rails are secured together, a diamond-shaped cavity formed in the block and by the rails, with a diamond-shaped hard-metal plate mounted in said cavity and hav-

ing flangeways cut therein, substantially as described.

4. As a new article of manufacture, a diamond-shaped hard-metal center plate for a crossing, having flangeways cut therein, forming four diamond-shaped projections, substantially as described.

In witness whereof the said VICTOR ANGERER and WILLIAM SELFRIDGE have here-

unto set their hands in the presence of two to
subscribing witnesses.

VICTOR ANGERER.
WILLIAM SELFRIDGE,
Executor of the estate of Edward Samuel, deceased.
